STRAND SEPARATING AND CLEANING
DEVICE FOR TWISTED CLOTHESLINESDouglas Malcolm MacKenzie, Toronto, Ontario,
Canada

Application November 2, 1948, Serial No. 57,956

2 Claims. (Cl. 211—119.13)

1

This invention relates to a strand separating device for clothes lines comprising two or more strands of wire or rope twisted together on a relatively long pitch and held under tension, to grip, between the strands, articles suspended therefrom to make unnecessary the use of clothes pins or clothes pegs.

Clothes lines comprising two strands of wire or rope more or less permanently twisted together for securing articles between the twisted strands are relatively well known. Also, devices for separating or spreading short lengths of the twisted strands to permit the insertion or withdrawal of articles are known.

In general, the twisted clothes lines of the prior art comprise two strands of wire more or less permanently twisted together under tension on a relatively long pitch. A strand separating device comprising a frame having a rotatable disc mounted therein is secured adjacent to one or other of the pulleys over which the clothes line is extended. Two holes are bored in the disc and an individual strand of the clothes line is passed through each of the holes. The twisted strands of the clothes line are separated and spread apart for a short distance of their length adjacent to the spreading device by drawing the clothes line towards and through the spreader, the rotation of the disc serving to untwist the strands as the line approaches the spreader and to hold them separated for a short distance after they leave the spreader, the rotation of the disc in its frame making this possible. An alternative arrangement is that in which the clothes line is of the non-movable type and the strand separating device is adapted to be moved along the line from one fixed end to the other.

The design of the twisted clothes line offers no particular difficulties in its manufacture and use. However, it is found, in the application of this type of clothes line on a commercial scale, that the strand separating device is subject to important difficulties in that the rotating member tends to bind or seize in its frame due to the separate and angularly disposed stresses to which the rotating disc is subjected, making it difficult, if not impossible to separate the strands. Also, the clothes lines normally are permanently set up out of doors and the strand separator is exposed to weather conditions which facilitate deterioration of the moving parts.

A principal object of this invention is to provide a strand separating device by means of which two or more of the strands of a twisted clothes line may be separated easily at the point or points required without binding or seizing.

A further object of the invention is to provide a strand separating device in which the move-

2

able parts are freely rotatable within their housing regardless of the angular disposition of the forces acting upon them, and in which the tendency to bind or seize is eliminated.

5 A further object of the invention is to provide a strand separating device for twisted clothes lines which may be employed for separating and spreading, without danger of binding or seizing, the twisted strands of a clothes line comprised of two, three, four or more strands twisted together on a relatively long pitch.

10 A further object of the invention is to provide a strand separating device which may be manufactured inexpensively, and which is easily assembled and installed.

15 Still further objects of the invention are to provide a strand separating device which is sealed against the entrance of dirt and moisture and in which provision is made to clean the individual strands of the clothes line as they are passed through it.

20 The strand separating device of the present invention comprises a cylindrical housing having open ends, a hollow cylindrical body rotatably mounted in and carried by the housing, a ball bearing raceway between the body and the housing, a spindle journaled in and extending transversely of said body, and pulleys rotatably mounted in axial alignment on said axle.

25 30 An understanding of the invention may be had from the following description, reference being made to the accompanying drawing, in which:

Figure 1 is a side elevation of an endless clothes line formed of twisted strands incorporating the strand separating device of the present invention;

35 Figure 2 is a cross-sectional elevation of a strand separating device incorporating the improvements of the present invention;

Figure 3 is an elevation in section taken along the line 3—3, Figure 2;

Figure 4 is a perspective view of the pulley and spindle arrangement;

Figure 5 is an elevation taken along the line 40 45 5—5, Figure 2, and

Figure 6 is a front view of one cap.

Like reference characters refer to like parts throughout the specification and drawings.

The clothes line illustrated in Figure 1 comprises two or more strands 10 of wire or rope more or less permanently twisted together on a relatively long pitch. The clothes line is of the endless type and is extended over spaced apart pulleys 11 and 12 rotatably mounted on shafts journaled in frames 13 which normally are carried by standards or other suitable clothes line supporting members.

The strand separating device comprises a hous-

ing 15 having open ends, a hollow cylindrical body 16 rotatably mounted in and carried by the housing, a shaft or spindle 17 journaled in and extending transversely of the hollow cylindrical body, and pulleys 18 and 18a rotatably mounted in axial alignment on the shaft. 5

The housing 16 is of cylindrical shape and is open at the ends. The rear periphery of the housing is drilled and tapped, as indicated by the numeral 20 to receive the arms 21 which form a yoke by means of which the device may be secured to one or other of the adjacent pulleys 11 or 12.

An internal peripheral groove 22 is formed in the internal wall of the forward end of the housing which is adapted to receive the ball bearings 23. 15

The rearward end of the hollow cylindrical body 16 is journaled in the forward end of the housing. Preferably, an external shoulder 24 is formed on the rearward end of the cylindrical body and an external peripheral groove 25 is formed in this shoulder adapted to mate with the groove 22 in the housing to form a ball bearing raceway. 20

A shaft or spindle 17 is journaled in opposing sides of the forward end of the body 16, extending at right angles to the long axis of the body. The ends of the spindle are journaled in small aligned openings or slots which are formed in the internal wall of the body. Preferably, a sleeve 17a is mounted on the axle. 30

Grooved pulleys 18-18a are rotatably mounted in axial alignment on the sleeve 17a. These pulleys are formed with grooves 19 over which the separated strands of the clothes line may be extended. Preferably, ball bearings 29 are inserted in a groove formed in the opposing faces of the bores of pulleys and the sleeve 17a to provide substantially frictionless rotation of the pulleys on the sleeve. 35

An end closure member, such as a cap 30, is fitted into the forward end of the body 16. This cap is formed with spaced openings 31 aligned with the pulleys 18-18a through which the separated strands are extended to the pulleys 18-18a. 40

A cap 32 is fitted into the rearward end of the body 16. This cap also is formed with spaced openings through which the separated strands extend to the pulleys 18-18a. This cap is provided with a rearwardly extending threaded stem 33. A felt washer 35 is pressed on the stem to fit closely within the rearward end of the body against the cap 32. This felt washer is also formed with spaced openings which may be brought into alignment with the openings in the cap 32. The felt is retained in place by a nut or thumb screw 34 turned on the threaded stem 33. 50

The caps 30 and 32 serve to keep dirt and moisture out of the body and the felt washer serves to clean the individual strands of the clothes line as they are passed through it. 55

In use, the clothes line is extended through the housing and the hollow cylindrical body and an individual strand is extended over each of the pulleys. The device may be secured firmly to one or other of the pulleys over which the endless clothes line is extended and the clothes line passed through the device to separate the strands for a short distance of their length, after which the strands resume their normal, tightly twisted relation. Alternatively, if the device is used with

a fixed clothes line, it may be slid along the line from one end to the other to separate the strands for a short distance of their length.

I have found that the spreading device of the present invention has a number of important advantages. The arrangement of the housing and cylindrical body permits substantially frictionless rotation of the body about an axis parallel to the clothes line extended through the body. Also, the manner in which the pulleys are mounted on the axle permits substantially frictionless rotation of the pulleys. The parts are free running without danger of seizing or binding. Also, the device may be made inexpensively of materials which may be exposed to all types of weather conditions without deterioration.

It will be understood, of course, that modifications may be made in the preferred embodiment of the invention described and illustrated herein without departing from the scope of the invention defined by the appended claims.

What I claim as new and desire to protect by Letters Patent of the United States is:

1. A strand separating device for clothes lines having two twisted strands which comprises a cylindrical housing having forward and rearward open ends, a hollow cylindrical body rotatably mounted in and carried by the forward end of the housing, a ball bearing raceway between the body and the housing, a spindle journaled in and extending transversely of the body at right angles to the long axis of the housing, grooved pulleys rotatably mounted in axial alignment on the spindle, caps adapted to close the ends of the body, spaced openings in each of said caps in alignment with said pulleys, wire cleaning means mounted at the rearward end of said housing, and spaced openings in said wire cleaning means in alignment with the openings in the rearward cap. 25

2. A strand separating device for clothes lines having two twisted strands which comprises a cylindrical housing having forward and rearward open ends, a hollow cylindrical body rotatably mounted in and carried by the forward end of the housing, a ball bearing raceway between the body and the housing, a spindle journaled in and extending transversely of the body at right angles to the long axis of the housing, grooved pulleys rotatably mounted in axial alignment on the spindle, caps adapted to close the ends of the body, spaced openings in each of said caps in alignment with said pulleys, a washer formed of fibrous material mounted at the rearward end of said housing, and spaced openings in said washer in alignment with the openings in the rearward cap. 35
